Primary Examiner — Kelley Donnelly(74) *Attorney, Agent, or Firm* — Robert C. Montgomery; Montgomery Patent & Design(57) **CLAIM**

The ornamental design for a portable solar light holder, as shown and described.

DESCRIPTION

FIG. 1 is an isometric view of a portable solar light holder illustrating a main structure portion and a drawer portion in juxtaposition with each other;

FIG. 2 is an isometric view of the main structure portion;

FIG. 3 is front view of FIG. 2;

FIG. 4 is a rear view of FIG. 2;

FIG. 5 is a left-hand side view of FIG. 2, wherein a right-hand side view is a mirror image of the left-hand side view;

FIG. 6 is a top view of FIG. 2;

FIG. 7 is a bottom view of FIG. 2;

FIG. 8 is an isometric view of the drawer portion;

FIG. 9 is a front view of FIG. 8;

FIG. 10 is a rear view of FIG. 8;

FIG. 11 is a left-hand side view of FIG. 8, wherein a right-hand side view is a mirror image of the left-hand side view;

FIG. 12 is a top view of FIG. 8;

FIG. 13 is a bottom view of FIG. 8, and;

FIG. 14 is another isometric view of the portable solar light holder with the main structure portion and drawer portion compiled together.
